UNITED STATES PATENT OFFICE.

MARY J. McARTHUR, OF CLEVELAND, OHIO.

WINDOW BOX.

Application filed July 7, 1922. Serial No. 573,369.

To all whom it may concern:

Be it known that I, MARY J. McARTHUR, a citizen of the United States, and a resident of Cleveland, in the county of Cuyahoga and State of Ohio, have invented a new and Improved Window Box, of which the following is a full, clear, and exact description.

This invention relates to improvements 10 in window boxes, and more particularly to window boxes for storing food, an object of the invention being to provide a window box which is located inside of the room, and mounted to move vertically on a window 15 frame so that it can be positioned at the upper portion of the frame with the upper sash lowered to permit a circulation of air through the box without chilling the room, and which can be lowered when it is desired 20 to remove articles from the box or place articles therein.

A further object is to provide a window box of the character stated, which is especially adapted for use in apartments and 25 the like, where boxes cannot project outside of the building by reason of fire regulations or rules of the apartment house, and which can be conveniently and easily installed at a minimum of expense.

30 A further object is to provide a window box of the character stated, which can be thoroughly cleaned from time to time thus resulting in a sanitary apparatus and one which permits of free circulation of air to 35 preserve the food without chilling the room.

A further object is to provide a window box construction of the character described, which can be conveniently shipped in a relatively small space or package, and can be assembled 40 and placed in position by anyone of average intelligence not requiring skilled labor.

With these and other objects in view, the invention consists in certain novel features 45 of construction and combination, and arrangement of parts, as will be more fully hereinafter described and pointed out in the claims.

In the accompanying drawings— 50 Figure 1 is a perspective view showing my improved window box in its normal elevated position.

Figure 2 is a view in vertical section

through the center of the box and the window frame with the box in its elevated position. 55

Figure 3 is a view similar to Figure 2 showing the box in its lowered position.

Figure 4 is a view in transverse section on the line 4—4, of Figure 3. 60

Figure 5 is a fragmentary view in longitudinal section through one end of the box illustrating a form of knocked down box.

Figure 6 is a view in transverse section of the box shown in Figure 5. 65

Figure 7 is a perspective view of my improved box detached.

Figure 8 is a view showing the box in knocked down form.

1 represents a window frame provided 70 with the ordinary upper and lower sliding sashes 2 and 3. 4 represents my improved window box, which is of general oblong shape having a bottom 5 which extends beyond the walls of the box and a back 6 which 75 also extends beyond the ends of the box.

The ends 7 and back 6 of the box are preferably joined to the top 8 and bottom 5 of the box by tongue groove connection 9 and secured by hooks 10 and eyes 11, and dowel pins 12 are also employed to connect the parts and hold them rigidly together. By reason of this arrangement of hooks and eyes and tongue and groove connection, I am enabled to ship the box in knocked down 85 form so that it can be assembled by the purchaser and reduce the cost of packing and shipment to a minimum.

To the end 7 doors 13 are connected by 90 hinges 14, and constitute the front of the box, said doors being secured together in any approved manner, and I have shown a hasp 15 with staple 16 for the reception of a padlock not shown, although the invention is of course, not limited to the manner of 95 locking the doors.

Metal strips 17 are secured to the back 6 at the ends of the latter, and constitute tongues, which are mounted to slide in guide rails 18 which are fixed to the upright members of the window frame 1 permitting the box to slide throughout the length of the upper sash, and angle brackets 19 constituting stops are secured to the frame 1 and engage the bottom 5 and limit the downward 105 movement of the box. These brackets also

prevent the box from interfering with the opening or closing of the sashes in case of fire or for any other purpose.

When the box is in its normal elevated position and the upper sash 2 loweved, as shown in Figure 2, the edge of the box bottom 5 engages a strip 20 secured to the top rail 21 of upper sash 2 to exclude the air from the room, and a strip 22 is secured to the meeting rail 23 of lower sash 3 and engages the glass 24 of upper sash 2 to also exclude the air and prevent chilling the room, although exposing the box to the outside air.

When the box is lowerd as shown in Figure 3, the bottom 5 is in line with strip 22 so that when the upper sash is closed the outside air is excluded.

To permit a free circulation of air through the box the back 6 of the box is perforated as shown at 25 and perforated top bottom and end partitions 26, 27 and 28 respectively are located in the box and spaced slightly from their adjacent walls so as to allow the air to circulate around inside of the box and keep the food in good condition.

I preferably provide a strip 29 which is secured to the upper portion of the window frame 1 and supports a series of (preferably 3) pulleys 30, and provide chains or other flexible connecting devices 31 and 32 for operating the box.

The projecting ends of bottom 5 are provided with openings 33 and through these openings a chain is passed and a hook 34 on one end of the chain is connected through a loop of the chain to couple the chain to the box. The chains 31 and 32 are passed over the pulleys 30 and are provided with rings 35 which are adapted to engage a hook 36 on the window frame and support the box in elevated position.

When it is desired to lower the box, these 45 are disengaged from the hook and the box allowed to slide downwardly into the position shown in Figure 3, where it is in convenient reach.

It will be noted that with my improved box the latter is normally elevated with the upper sash lowered to allow a free circulation of air through the box while the air is excluded from the room. In this position the box is out of the way, and be-

ing on the inside of the room does not disfigure the outside of the building and does not interfere with the use of the window any more than an ordinary awning.

When the box is lowered it is in convenient reach, and at all times the box and sashes can be manipulated so as to prevent chilling the room in the coldest weather, and result in economy to the user in that the necessity of furnishing ice in cool weather is prevented.

While I have illustrated what I believe to be a preferred embodiment of my invention, I would have it understood that I do not limit myself to the precise details set forth, but consider myself at liberty to make such changes and alterations as fairly fall within the spirit and scope of the appended claims.

I claim:

1. The combination with a window frame, and upper and lower sliding sashes, of a window box, rails secured to the sides of the window frame and providing vertical sliding mounting for the box, pulleys located at the upper portion of the frame, flexible devices fixed to the ends of the box and passed over the pulleys, means engaged by the devices for holding the box in its elevated or lowered position, strips fixed to the upper rails of both sashes, and an extended bottom on the box engaging one of these strips when the box is in raised position and the upper sash lowered, and engaging the other of said strips when the box is lowered.

2. The combination with a window frame, and upper and lower sashes, of a window box, rails secured to the inner faces of the vertical sides of the window frame, back extensions on the box mounted to slide in said rails, pulleys mounted at the top of the window frame, bottom extensions on the box at its end, flexible devices secured to said bottom extensions and passed over said pulleys, inwardly projecting strips fixed to the back of both sashes, and a bottom extension on the box engaging one of these strips when the box is in raised position and the upper sash lowered and engaging the other of said strips when the box is lowered.

MARY J. McARTHUR.
